UNITED STATES PATENT OFFICE.

CHARLES N. BARTON, OF HARRISBURG, ILLINOIS, ASSIGNOR OF ONE-HALF TO JAMES B. BLACKMAN, OF HARRISBURG, ILLINOIS.

CUTTING-BIT FOR CHAINS OF MINING-MACHINES.

1,078,082.

Specification of Letters Patent.

Patented Nov. 11, 1913.

Application filed February 10, 1913. Serial No. 747,397.

To all whom it may concern:

Be it known that I, CHARLES N. BARTON, a citizen of the United States of America, residing at Harrisburg, in the county of 5 Saline and State of Illinois, have invented certain new and useful Improvements in Cutting-Bits for Chains of Mining-Machines, of which the following is a specification.

10 This invention relates to improvements in mining machines of the cutting chain type, and more particularly to the construction of the cutting bit or tooth therefor; and it has for its primary object the provision of 15 a bit which may be reversed in its mounting and which will be provided with a plurality of effective cutting ends or points whereby when one becomes worn or destroyed, the other one may be readily and effectually 20 presented for use.

Another object of the invention is the provision of means traversing the axis of the bit-way and provided with a coacting surface which may be advanced into mutual engagement with a similar surface of the bit and held, so as to hold the bit operatively 25 projected to perform its function.

A further object of the invention is the provision of a bit having two of its surfaces 30 provided with teeth; a mounting provided with a bit-way and having one of its walls provided with co-engaging teeth, and an impinging or clamping member traversing the bit-way and provided with a surface coacting 35 with one of the toothed surfaces of the bit and operating to effect adjustments of the bit, so as to bring the other surface of the bit and the coacting surface of the mounting into operative engagement.

40 With these and other objects in view, the invention consists of certain novel features of construction, combination and arrangement of parts, as will be hereinafter described and claimed.

45 In the accompanying drawings:—Figure 1 is a side view of a chain link, showing the bit in its applied position thereto; Fig. 2 is a vertical section therethrough, showing the bit in elevation; Fig. 3 is a top plan view of the link and bit; Fig. 4 is a perspective view of the bit; and Fig. 5 is a perspective view of the impinging or clamping member.

The link 1 is provided at one side with 50 an integral lug 2, in which is formed a bit-

way 3 disposed diagonally to the longitudinal plane of the link and provided with a wall having transversely arranged teeth or corrugations 4. The bit-way opens onto the opposite sides of the link, and as illustrated 55 said bit-way is adapted to adjustably receive a correspondingly formed bit 5 having identically constructed effective cutting points 6 which extend beyond the opposite ends of the bit-way when the key is applied 60 so that one of the points will be operatively projected to perform its function.

A guide slot 7 is formed in the lug or mounting 2 and is arranged to traverse the bit-way 3 and to slidably accommodate an 70 impinging member 8. The impinging member is preferably of rectangular configuration, conforming transversely with the slot 7, so that the member will be positively held against turning. The impinging member is 75 provided with a longitudinally extending slot 9 having a length exceeding the width of the bit 5, so that the latter may be freely advanced through the slot in the operation of initially fixing the bit upon the link. The 80 end wall 10 of the slot 9 lies parallel with the toothed wall 4 of the bit-way 3, so as to form a guiding surface to properly deflect one of the points 6 into the branch 3a of the bit-way when the impinging member is ad- 85 justed to a released position. This construction is desirable in that the bit may be advanced into the bit-way with facility and freedom. A wall 11 of the impinging member 8 lies parallel with the wall 4 of the 90 mounting or lug 2, and is provided with transversely extending teeth which are adapted for interfitting engagement with either set of teeth or corrugations 12 on two edges of the bit. The toothed wall 11 of the 95 impinging member is disposed to one side of the plane of the toothed wall 4 of the mounting 2 whereby when the impinging member is adjusted to an operative clamped position the surface 11 will be drawn into 100 mutual contact with one of the surfaces 12 and then tend to tilt the bit and cause the surface 4 to be brought into interlocking engagement with the other set of teeth 12 on the bit. The impinging member is provided 105 with a reduced cylindrical shank 13, which is threaded for the reception of a clamping nut 14. The shank extends through a passage 15 in one end of the mounting 2, and as illustrated in Fig. 2 the nut may be ad- 110

justed to bear against one end of the mounting and thereby retain operative adjustments of the impinging member and bit respectively.

5 From the construction described, it is evident that the cutting bit may be reversed at the discretion of the operator, so that when one of the cutting points 6 is worn or destroyed another point may be quickly substituted therefor. The fact that the impinging member 8 is provided with a toothed surface 11 mutually co-operating with similar surfaces of the bit, insures operative retention of the bit and affords means 10 for effecting such retention without resulting in injuring the toothed surfaces of the bit during the clamping operation.

Having thus described my invention, what I claim is:—

20 The combination of a chain link having a lug formed with a key-way of rectangular cross section passing through the body of the lug, and in the lengthwise direction thereof, and an intersecting and longitudi-

nally disposed slot of rectangular cross section; said keyway provided on a portion of one wall thereof with a plurality of corrugations; a block of rectangular design slidably mounted in said longitudinal slot of rectangular cross section, and provided with a 25 key-way adapted to register with the key-way in the lug; the wall of the key-way of the slideable block opposite the corrugations of the first named key-way being provided with corrugations; a bit fitting within said registering key-ways and projecting at either end beyond the lug and link, said bit having a pair of opposite walls thereof 30 formed with corrugations adapted to engage with the corrugations of said key-ways; and 35 a device for clamping said slideable block to secure the bit in position.

In testimony whereof I affix my signature in presence of two witnesses.

CHARLES N. BARTON.
